UNITED STATES PATENT OFFICE.

JOHN C. BUSH, OF DULUTH, MINNESOTA.

CLOTHES-LOCKER.

1,249,594.

Specification of Letters Patent. Patented Dec. 11, 1917.

Application filed December 16, 1916. Serial No. 137,350.

To all whom it may concern:

Be it known that I, JOHN C. BUSH, a citizen of the United States of America, and resident of Duluth, in the county of St. 5 Louis and State of Minnesota, have invented certain new and useful Improvements in Clothes-Lockers, of which the following is a specification.

This invention relates to furniture and it 10 has particular reference to clothes lockers and more particularly to individual compartments for containing or holding garments; the said invention being of utility in schools, work-shops, or other places where 15 people have to deposit their coats or other articles of apparel for considerable periods of time, as during school sessions or working hours.

An object of this invention is to provide 20 clothes holders which may be arranged in groups and changed to increase or diminish the number in any one group, the sections being successively interlocked with the contiguous sections, so that a strong and durable 25 union is effected for holding them in proper positions, the said invention also having for its object the provision of a heading or cover for the upper ends of the sections, said invention furthermore contem- 30 plating the provision of novel means for forming a conduit for the passage of air, the said air passage being in communication with each of the compartments whereby the same compartments are ventilated and the 35 contents of the compartments may be aired.

With the foregoing and other objects in view, the invention consists in the details of construction, and in the arrangement and combination of parts to be hereinafter more 40 fully set forth and claimed.

In describing the invention in detail, reference will be had to the accompanying drawings forming part of this specification, wherein like characters denote corresponding 45 parts in the several views, and in which—

Figure 1 illustrates a view in elevation of a clothes holder, embodying the invention;

Fig. 2 illustrates a sectional view on the 50 line 2—2 of Fig. 1;

Fig. 3 illustrates a sectional view on the line 3—3 of Fig. 1; and

Fig. 4 illustrates a perspective view of a fragment of one of the sections.

55 In these drawings 5, 6, and 7 denote the

compartment sections and it will be understood that the intermediate sections may be duplicated to increase the number of compartments and the said sections have interlocking joints such as shown at 8 and 9, so 60 that they may slide longitudinally and when assembled are held against movement. The end sections 5 and 7 have their outer sides extended to form brackets 10 and 11 respectively, and the said brackets are intended to 65 be anchored against a wall or other support 12 so that the sections will be comparatively rigid and held against displacement. A backing strip 13 and a cover or head strip 14 are provided at the tops of the sections and 70 the backing strip serves as an anchorage for the shanks 15 of clothes hooks 16, whereas the head 14 serves as a support for the hooks 17 and furthermore, it constitutes a protector for the contents of the receptacles or 75 a support for a curtain or the like, when such a curtain is used for protecting the garments.

In Fig. 2, the dotted lines denote that the corners of the sections may be square rather 80 than rounded and when made square, the head 14 is a more effective protection for the contents of the receptacles or compartments.

Each compartment has a branch pipe 19 85 and a sectional conduit 20 which is to interlock or register with the sectional conduits of other sections, so that when they are joined, an air duct is formed for the circulation of air, as stated. Of course, the air 90 may be forced through the duct into the pipes or other means of circulation may be employed.

In order to properly connect the sections of the conduits together, one end of each 95 conduit has a lip or projecting bottom portion 21 and a notched under surface 22 at the opposite end, the lip of one end being designed to fit the notched portion of the next 100 succeeding conduit section so that when they are coupled together, they will have the appearance of the conduit shown in Fig. 3, the said Fig. 3 giving a very clear conception of the construction and relation of parts which in connection with the other illustrations is believed sufficient to enable those skilled in the art to practise the invention.

It is understood, of course, that the sections are preferably constructed of metal 110 and hence can be easily renovated and kept

in a sanitary condition, especially so, as the current of air through the compartments insures proper airing of the garments.

I claim

5 In a clothes locker, a series of curved sections, the contiguous sections having interlocking joints by which they are connected, brackets on the end sections, means supplying air to the said lockers, comprising pipes

communicating with the interior of the compartments, duct sections carried by the said pipes, each of said sections having a projecting bottom forming a lip at one end, and a recessed bottom forming a seat for the lip of the contiguous section of the next succeeding compartment.

JOHN C. BUSH.
